UNITED STATES PATENT OFFICE.

SAMUEL W. BOOTH, JR., OF ST. LOUIS, MISSOURI.

SEAL-LOCK.

1,188,886.

Specification of Letters Patent. Patented June 27, 1916.

Application filed December 3, 1915. Serial No. 64,801.

To all whom it may concern:

Be it known that I, SAMUEL W. BOOTH, Jr., a citizen of the United States, residing at the city of St. Louis, in the State of Missouri, have invented certain new and useful Improvements in Seal-Locks, of which the following is a specification.

This invention relates to sealing devices and more particularly to sealing devices for 10 gas meters, car doors, and the like comprising a frangible socket member and a shank member having spring means for engaging and locking the socket member and shank member together, and has for its object to 15 provide an efficient device of the character described which may be readily applied and removed by the person having authority to do so, and is economical to manufacture.

One of the advantages of the device embodying the present invention is that the 20 spring locking means may be readily attached to the shank or removable therefrom for purposes of repair, and when in locking position firmly engages the socket member 25 at a plurality of points.

In the accompanying drawings forming part of this specification wherein like numbers of reference denote like parts wherever they occur, Figure 1 is a view showing 30 the device embodying the present invention applied in locking and sealing position, the parts on which the device is applied being shown in fragmentary cross section. Figs. 2 and 3 are views on an enlarged scale showing 35 the spring-bearing portion of the shank being inserted into the hollow frangible cap, the cap being shown in section; Fig. 4 is a view on an enlarged scale showing the frangible cap in cross section moved to sealing 40 position with the spring of said spring-bearing shank entirely within the hollow portion of said cap; and Fig. 5 is a sectional view on the line 5—5, Fig. 4.

A shank 1 of any suitable length and 45 transverse dimension may bear an enlarged base 2 at one end thereof and a reduced portion 3 at the opposite end, said shank, base, and reduced portion being preferably formed in one piece and may be made of 50 metal or the like in the cylindrical shape, shown in the drawings, and is constructed of material not readily frangible. A member 4 having two or more laterally extending spring prongs 5 is borne by an end of 55 reduced portion 3 and may be secured thereto in any suitable manner such, for instance,

as by means of rivet 6 or the like, said prongs being adapted to be pressed toward said reduced portion as same is forced through reduced opening 7 of hollow portion 8 of frangible cap 9, said prongs being adapted to spring away from said pressed position when said reduced portion and said prongs have entered entirely into said hollow portion, as shown in Fig. 4, so that shank 1 will substantially register in said reduced opening and the parts will be held in sealed relation as shown in said Fig. 4. Cap 9 may be made of any suitable frangible material such, for instance, as cast iron, porcelain, glass or the like, and when the parts embodying the device of this invention are in sealing position, shown in Fig. 4, a blow of a hammer or the like upon cap 9 will break same thus breaking the seal without damaging shank 1 and its parts or member 4 and its spring prongs.

A suitable manner of applying the device of this invention as a sealing lock for locking together two parts, such, for instance, as parts 10 and 11, is shown in Fig. 1, wherein shank 1 is inserted through appropriate openings 12 and 13 borne by parts 10 and 11, respectively, with the end of said shank bearing reduced portion 3 and member 4 with spring prongs 5 protruding outwardly through opening 13, and cap 9 being slipped over said prongs as shown in Figs. 2 and 3 to the position shown in Fig. 4 so that said prongs having passed entirely within hollow portion 8 of cap 9 through reduced opening 7, said prongs will spring away from reduced portion 3 so that the ends of said prongs will be engageable against the walls of said hollow portion adjacent said reduced opening to prevent said cap from being removed from sealing position shown in aid Fig. 4, which is the position of said cap shown, also, in Fig. 1, thus sealing parts 10 and 11 between enlarged base 2 and said cap, a portion of shank 1 adjacent reduced portion 3 substantially registering in reduced opening 7, as best seen in Fig. 4.

To break the seal hereinabove described, it will be necessary merely to break cap 9 by means of a blow of a hammer or the like and to remove the broken cap or to let same fall from its sealing position in association with shank 1 and the parts borne by said shank, whereupon said shank and said parts borne thereby may be removed from openings 12 and 13 and the parts 10 and 11 will

no longer be locked together. It will be observed that in breaking said seal the only part of the device of this invention that is damaged or destroyed is frangible cap 9, which may easily and cheaply be replaced by a new cap for completing the parts of the device for use on another occasion.

In the drawings, shank 1 is shown to be a relatively short straight piece longitudinally, but it is, of course, understood that said shank may be relatively long if desired, and, also, that same may be curved or otherwise extended longitudinally from its base 2 to its reduced end portion 3.

15 I claim:

A sealing device comprising a shank hav-

ing an enlarged base and a reduced head, a spider-like member permanently secured to the outer extremity of said reduced head and flush therewith, said member being formed with radial spring arms having two pairs of integral angularly and rearwardly bent spring prongs, and a hollow frangible member having a reduced outward opening, said spider-like member being adapted to be inserted into said hollow member through said opening with the terminal ends thereof engaging within said hollow member.

20 In testimony whereof I hereunto affix my signature.

25 SAMUEL W. BOOTH, JR.
